UNITED STATES PATENT OFFICE.

JAMES A. WILLARD, OF CHATTANOOGA, TENNESSEE, ASSIGNOR OF THREE-FOURTHS TO WILLIAM M. LASLEY, THEODORE LASLEY, AND CHARLES L. HALL, OF CHATTANOOGA, TENNESSEE.

CENTRIFUGAL MACHINE.

SPECIFICATION forming part of Letters Patent No. 744,659, dated November 17, 1903.

Application filed June 12, 1903. Serial No. 161,239. (No model.)

To all whom it may concern:

Be it known that I, JAMES A. WILLARD, a citizen of the United States, residing at Chattanooga, in the county of Hamilton and State 5 of Tennessee, have invented new and useful Improvements in Centrifugal Machines, of which the following is a specification.

This invention relates to certain new and useful improvements in centrifugal ma- 10 chines.

The invention aims to construct a centrifugal machine which is especially adapted for the continuous extracting of liquid from cotton or wool and is so constructed as to con- 15 stantly receive the material which is fed thereto in a uniform manner, extracting the liquid therefrom, and delivering the material after it has been operated upon out of the machine without having to make the necessary stops 20 for the loading and unloading of the material, therefore obtaining a great saving of time and labor.

The invention further aims to construct a centrifugal machine for the continuous ex- 25 tracting of liquid from cotton or wool which shall be extremely simple in its construction, strong, durable, efficient in its operation, and comparatively inexpensive to set up.

With the foregoing and other objects in 30 view the invention consists of the novel combination and arrangement of parts herein- after more specifically described, illustrated in the accompanying drawing, and partic- 35 ularly pointed out in the claims hereunto appended.

In describing the invention in detail reference is had to the accompanying drawing, which illustrates a sectional elevation of my new and improved centrifugal machine.

Referring to the drawing by reference characters, 1 denotes a hollow supporting-base, which forms a receiving-chamber 2 for the treated material and is provided with a closed bottom 3 and a top 4, having an annular in- 45 let-opening 5. The top 4 is formed with a laterally - extending supporting - flange 6, which is continuous, and the top 4 is further provided at its inner side with an upwardly- 50 extending continuous flange 7, having a con- cave groove in its upper face, as at 8. The

base 1 is preferably cylindrical in contour, although any other preferred shape may be employed, and is provided with a suitable opening, so that the treated material can be exhausted therefrom in any suitable manner. 55

Mounted upon the base 1 is a cylindrical casing 9, which is adapted in a manner as herein set forth to form a chamber 10 for collecting the water. The casing 9 also forms what may be termed a "support" for various 60 parts of the machine and is provided at its lower end with a laterally-extending flange 11, resting upon the flange 6. The upper end of the casing 9 is provided with an inwardly- 65 extending annular supporting-flange 12, cut 70 away at one corner, as at 13, to form a ball- race, in which are mounted the bearing-balls 14. Projecting upwardly from the top of the casing 9 and extending over the said casing to a point approximately centrally thereof is 75 a bearing-bracket 15, the function of which will be hereinafter referred to. Projecting laterally and upwardly from the outer face of the casing 9 and substantially parallel with a portion of the bracket 15 is a substantially fork- shaped bearing-bracket, as well as a supporting-bracket 16. The brackets 15 and 16 are each provided with openings which register 80 with each other, as indicated by the dotted lines 17, and through these openings is adapt- 85 ed to extend a driven shaft 18, having connected to its outer end an adjusting-screw 19, which extends through a part of the bracket 16 and is connected to the shaft 18. The lat- 90 ter carries on its inner end a cone-shaped pulley 20, the latter forming a friction-drive in a manner as hereinafter set forth. The pulley 20 is secured upon the shaft 18 by means of the fastening device 21. Mounted upon the shaft 18 is a drive-pulley 22, which 95 is operated by means of a belt 23, driven by the pulley 24 upon the drive-shaft 25. The latter at its inner end is supported by the box- 100 ing 26, mounted on the flange 11, and at its outer end is supported in a standard 27.

The reference character 28 denotes a cylinder which is perforated throughout and open at its top and bottom, so there will be no interruption to the material when it is fed to the cylinder or discharged therefrom. This

is essential, for the reason that cotton and wool have a tendency to hang together. Consequently if there were anything extending over the mouth of the cylinder or the open bottom thereof it would cause the same to become choked up. The cylinder 28 is arranged within the casing 9 and is supported at its bottom upon the flange 7 and projects slightly within the opening 5 of the top 4 of the base 1. The manner of supporting the lower end of the cylinder 28 is as follows: To the outer face of the cylinder is secured an annular band 29, substantially L-shaped in cross-section, and has its lower face provided with a convex-shaped groove 30. The grooves 8 and 30 register with each other and form a ball-race in which are mounted the bearing-balls 31. The cylinder 28 then, through the intervention of the band 29, rests upon the bearing-balls 31. The upper end of the cylinder 28 is supported upon the inwardly-extending flange of the casing 9, and the manner of supporting the cylinder 28 is as follows: The top of the cylinder 28 has secured there-
to an annular collar 32, having its upper face beveled, as at 33, and provided with the depending lug 34, the latter being secured to the cylinder 28. The collar 32 is of such width as to project a suitable distance over the top of the cylinder 28 and to further project laterally therefrom. This lateral extension of the collar 32 rests upon the supporting-flange 12, or rather upon the bearing-balls 14, the latter also bearing against the outer face of the depending lug 34. The beveled surface 33 of the collar is adapted to be engaged by the cone-shaped pulley 20, so that when motion is imparted to the shaft 18, carrying the cone-shaped pulley therewith, the engagement between the pulley and the beveled surface 33 will cause the cylinder 28 to be revolved.

Arranged approximately centrally of the base 1, in the bottom thereof, is a box or journal 35 for the lower end of the vertically-extending shaft 36. The shaft 36 extends upwardly through the base 1, the cylinder 28, and the free end of the bracket 15, the shaft 36 projecting a suitable distance above the bracket 15 and carrying on this projecting end a drive-pulley 37, which is operated by means of the belt 38, the latter passing over the idler-pulley 39, supported by the bracket 16, and then downwardly over the drive-pulley 40, mounted upon the drive-shaft 25. The shaft 36 carries a spiral conveyer 41, the width of the same being such as to extend from the periphery of the shaft to almost the inner face of the cylinder 28, or, in other words, the width of the conveyer 41 is such that it extends from the periphery of the shaft to near the inner face of the cylinder 28, so that it will just clear the latter when the conveyer is operated. The length of the conveyer is such as to extend from the lower end of the cylinder 28 to very near the top thereof.

The shaft 25 is provided with the fast and loose pulleys 42 43, respectively connected with a suitable prime mover.

The chamber 10, hereinbefore referred to, is formed by the cylinder 28 and casing 9 and has communicating therewith the waste-pipe 44.

The machine is provided with a feed-table 75 for the material, and is indicated by the reference character 45. The table 45 rests upon the top of the casing 9 and is further supported by the vertical standard 46. The table 45 is provided with a conveyer-belt 46, 80 operating over the rollers 47. The table 45 is also provided with a feed-roller 48 and guide-board 49. The roller 47 at the inner end of the feed-table 45 is of such diameter as to cause the conveyer-belt 46 to extend 85 slightly over the inner edge of the collar 32, so that the material will pass directly into the cylinder 28 in an uninterrupted manner. One of the rollers 47 is driven in any suitable manner so as to impart motion to the conveyer-belt 46.

The construction and arrangement of the operating means for the cylinder 28 and the spiral conveyer 41 are such that the conveyer will operate in the same direction as the cylinder 28, but at a slightly-greater speed.

The operation of the machine is as follows: The material is spread in an ordinary manner on the conveyer-belt 46, and when motion is imparted thereto the material is delivered between the inner roller 47 and the feed-roller 48 and falls by gravity into the cylinder 28, it being understood that the cylinder 28 and spiral conveyer are operating. The latter is driven in the same direction as the cylinder 28, but at a slightly-greater speed. The centrifugal force immediately draws the material to the inner surface of the cylinder or basket. The result is that the conveyer gradually works the material down until it is delivered out of the cylinder 28 in the chamber 2, where it is exhausted by any suitable means. It will be stated that the difference in speed between the cylinder 28 and spiral conveyer 41 is regulated so as to deliver the material 110 at any given time or to allow the material to have sufficient time in the cylinder 28 to properly remove all liquid from it. It will be evident that if the cylinder 28 and spiral conveyer 41 were traveling the same number 115 of revolutions the material would remain in the machine; but as soon as the travel of the spiral conveyer 41 is faster the material is gradually worked down and out. On the other hand, if the spiral conveyer 41 were stationary and the cylinder 28 traveling at a great speed, which is necessary to extract the water, the material would be passed through so quickly that it would not have sufficient time to remove the liquid. Consequently the 120 best results are obtained by running the spiral conveyer 41 at only sufficient additional speed to deliver the material in its best condition.

It is thought the many advantages of my new and improved centrifugal machine for the continuous extracting of liquid from cotton or wool can be readily understood from the foregoing description, taken in connection with the accompanying drawing, and it will furthermore be evident that changes, variations, and modifications can be resorted to without departing from the spirit of the invention or sacrificing any of its advantages, and I therefore do not wish to restrict myself to the details of construction hereinbefore described and as shown in the accompanying drawing, but reserve the right to make such changes, variations, and modifications as come properly within the scope of the protection prayed.

Having thus fully described my invention, what I claim as new, and desire to secure by Letters Patent, is—

1. A centrifugal machine for extracting liquid from wool, cotton and the like, comprising a perforated cylinder having its top provided with a beveled collar, a ball-bearing support for the top and bottom of said cylinder, means frictionally engaging with the beveled face of the collar for revolving the cylinder, a spiral conveyer arranged within said cylinder, and operating means for said conveyer.
2. In a centrifugal machine for extracting liquid from wool, cotton and the like, a perforated cylinder having uninterruptedly-open ends, a ball-bearing support for the top and bottom of said cylinder, means frictionally engaging with the top of said cylinder for revolving it, a spiral conveyer arranged within said cylinder, and operating means for said conveyer.
3. In a centrifugal machine for extracting liquid from wool, cotton and the like, a perforated revoluble cylinder having uninterruptedly-open ends, a spiral conveyer arranged in said cylinder, operating means for said conveyer, and operating means for said cylinder.
4. A centrifugal machine for extracting liquid from wool, cotton and the like, comprising a perforated revoluble cylinder having uninterruptedly-open ends, a spiral conveyer arranged in said cylinder, operating means for said conveyer, and means frictionally engaging with the top edge of said cylinder and adapted when operated to rotate the said cylinder.

5. In a centrifugal machine for extracting liquid from wool, cotton and the like, a hollow base, a casing mounted thereon, a perforated cylinder arranged within said casing and supported at its upper end upon said casing and at its lower end upon said base, said cylinder projecting in said base, a shaft extending through said base and cylinder, a spiral conveyer carried by the said shaft, means engaging with the top edge of said cylinder for rotating it, and means engaging with said shaft for rotating it.

6. In a centrifugal machine for extracting liquid from wool, cotton and the like, a base,

bearing-balls carried by said base, a casing mounted upon said base, bearing-balls carried by said casing, a perforated cylinder arranged within said casing and extending partly in said base, said cylinder at its top mounted upon the bearing-balls carried by said casing, and at its bottom mounted upon the bearing-balls carried by said base, a spiral conveyer arranged within said cylinder, means for rotating said cylinder, and means for rotating the said conveyer.

7. In a centrifugal machine for extracting liquid from wool, cotton and the like, a hollow base, a casing mounted thereon, a perforated cylinder arranged within said casing and supported at its upper end upon said casing and at its lower end upon said base, said cylinder projecting in said base, a shaft extending through said base and cylinder, a spiral conveyer carried by the said shaft, means frictionally engaging with the top edge of said cylinder and adapted when operated to rotate the said cylinder, and means engaging with said shaft for rotating it.

8. A centrifugal machine for extracting liquid from wool, cotton and the like comprising a base, bearing-balls carried by said base, a casing mounted upon said base, bearing-balls carried by said casing, a perforated cylinder arranged within said casing and extending partly in said base, said cylinder at its top mounted upon the bearing-balls carried by said casing and at its bottom mounted upon the bearing-balls carried by said base, a spiral conveyer arranged within said cylinder, means frictionally engaging with the top edge of said cylinder and adapted when operated to rotate the said cylinder, and means for rotating said conveyer.

9. A centrifugal machine for extracting liquid from wool, cotton and the like comprising a perforated cylinder having uninterruptedly-open ends, means for supporting the lower end of said cylinder, a collar carried by the upper end of said cylinder and provided with a bevel-face, means engaging the said collar for supporting the upper end of said cylinder, means frictionally engaging the said bevel-face of said collar and adapted when operated to rotate the said cylinder, a spiral conveyer arranged within said cylinder, and operating means for said conveyer.

10. In a centrifugal machine for extracting liquid from wool, cotton and the like, a perforated cylinder, a ball-bearing support for the lower end of said cylinder, a ball-bearing support for the upper end of said cylinder, means frictionally engaging with the top edge of said cylinder and adapted when operated to rotate said cylinder, a conveyer arranged within said cylinder, and operating means for said conveyer.

11. In a centrifugal machine for extracting liquid from wool, cotton and the like, a perforated cylinder having uninterruptedly-open ends, ball-bearings for supporting the lower end of said cylinder, ball-bearings for sup-

porting the upper end of said cylinder, means frictionally engaging with the top edge of said cylinder and adapted when operated to rotate said cylinder, a conveyer arranged within said cylinder, and operating means for said conveyer.

12. A centrifugal machine for extracting liquid from wool, cotton and the like consisting of a base having its top provided with an opening and an annular groove, bearing-balls mounted in the said groove, a casing mounted upon the said base and provided with an inwardly-extending flange having a groove, bearing-balls mounted in the said groove, a perforated cylinder arranged within said casing, a band carried by the lower end of said cylinder and adapted to be mounted upon the said bearing-balls carried by the top of the base for supporting the lower end of said cylinder, a collar carried by the top of said cylinder and provided with a bevel-face and adapted to rest upon the balls carried by the casing for supporting the top of said cylinder, means frictionally engaging the said bevel-face and adapted when operated to rotate the said cylinder, a spiral conveyer arranged within said cylinder, and operating means for the said conveyer.

13. A centrifugal machine for extracting liquid from wool, cotton and the like comprising a base having its top provided with an opening and an annular groove, bearing-balls mounted in the said groove, a casing mounted upon the said base and provided with an inwardly-extending flange having a groove, bearing-balls mounted in the said groove, a perforated cylinder arranged within said casing, a band carried by the lower end of said cylinder and adapted to be mounted upon the said bearing-balls carried by the top of the base for supporting the lower end of said cylinder, a collar carried by the top of said cylinder and provided with a bevel-face and adapted to rest upon the balls carried by the casing for supporting the top of said cylinder, a cone-pulley supported by said casing and

adapted to engage with said bevel-face and when operated to rotate the said cylinder, operating means for said pulley, a shaft extending through said base and cylinder and supported by the said base and casing, a spiral conveyer carried by the said shaft and adapted to be rotated when said shaft is operated, and means connected with the upper end of said shaft for operating it.

14. A centrifugal machine for extracting liquid from wool, cotton and the like comprising a perforated cylinder, supporting means therefor, means frictionally engaging with the top edge of the said cylinder and adapted when operated to rotate the said cylinder, a shaft extending through said cylinder, a spiral conveyer carried by said shaft, said conveyer of a width so as to extend from the periphery of the shaft to near the inner face of said cylinder, and means engaging the said shaft for operating it, causing thereby the rotation of said conveyer.

15. A centrifugal machine for extracting liquid from wool, cotton and the like consisting of a perforated cylinder having uninterruptedly-open ends, a ball-bearing support for the upper end of said cylinder, a ball-bearing support for the lower end of said cylinder, a shaft extending through said cylinder, a conveyer carried by said shaft and of a width so as to extend from the periphery of the shaft to near the inner face of said cylinder, means frictionally engaging with the top edge of said cylinder and adapted when operated to rotate the said cylinder, and means engaging the said shaft and adapted to operate the said shaft, causing thereby the operation of said conveyer.

In testimony whereof I have hereunto set my hand in presence of two subscribing witnesses.

JAMES A. WILLARD.
